LAJOS NEMÉNYI, OF MOUNT VERNON, NEW YORK

BOILER FEEDING DEVICE

Application filed December 19, 1925. Serial No. 76,373.

This invention relates to boiler feeding devices particularly adapted for use with low pressure boilers such, for example, as boilers made of cast iron.

Such low pressure boilers are used for central heating plants, for hot water supply, for disinfecting plants and for various industries. Heretofore these boilers have been supplied with water either from condensers in the system or under pressure through direct connections with water mains. In such cases the feed line, which is controlled by suitable valve means, is left open until the water flowing into the boiler reaches the mean water level of the boiler and the line is closed.

Frequently the engineer or person in charge through carelessness or with bad intent permits water to run into the boiler when the latter is overheated. With such cast iron boilers, the material thereof is, due to its lack of elasticity, unable to withstand the stresses resulting from the rapid cooling of certain parts thereof by the water admitted and different parts are broken and become useless, thus causing great expense for repair and the inconvenience of lengthy interruptions of service.

Direct feeding, that is, through direct connection between a water supply main or line and the boiler has the additional disadvantage that the hot water may, when the connection is open, be forced or sucked into the water pipe line. When the water pipe line and the steam boiler are directly connected and the pressure in the pipe line is less than the boiler pressure as, for example, when a pressure reduction occurs in the supply line, the hot water in the boiler will pass out of the boiler into the supply line.

It is well known that such aspiration of hot water into the water main will cause considerable damage and consequent interruption of service. For example, the lead packings of cast iron pipes are frequently loosened and leakage occurs; the aspirated water carries impurities into the water main and affects the quality of the water for drinking purposes; and as a result of the withdrawal of the hot water from the boiler, the

boiler parts may be burned and rendered useless.

An object of the present invention is to provide a boiler feeding device by which such disadvantages will be obviated.

Other and more specific objects and features will be brought out in the description and claims.

The figure illustrates an application of a preferred embodiment of the invention.

Steam passes from the boiler *a* through the main steam line *b* and the water of condensation in the system returns through the pipe *d* to the boiler where it is again changed into steam. Extending upwardly from the condenser line *d* is a pipe line *e* provided at an intermediate point with a shut-off valve *f*, and at its upper end with a tank *g*, preferably funnel-shaped and having its upper edge, as indicated in the drawing, at the mean water level of the boiler. Spaced above the upper edge of the tank *g* is a faucet *h* connected with a water main (not shown). Preferably the faucet *h* is at least four inches above the level of the upper edge of the tank *g*.

The operation of the apparatus is substantially as follows: Before starting the fire, valve *f* and faucet *h* are opened and both remain open until the water in the boiler reaches the mean water level thereof indicated by the filling of the funnel or tank *g*. Valve *f* and faucet *h* are then closed. Inasmuch as the upper edge of the funnel *g* is in the plane of the mean water level of the boiler, use of the device of the present invention prevents filling of the boiler above the mean water level and reduction of the steam space in the boiler. Furthermore, the boiler cannot be fed while it is hot, since the pressure in the feed pipe *e* up to the valve *f* is the same as that of the boiler, and, if the engineer or any other person attempts to feed the boiler while it is hot, he must open valve *f*, and the hot water at high temperature will be forced from the feed pipe *e*. In practical operation, valve *f* and faucet *h* are adapted for operation by detachable keys.

In case the engineer has failed to feed the boiler while cool enough and the boiler is hot

and under pressure, he must at once close the air and chimney drafts, open the furnace door so that cold air flowing into the firebox will cool the heating gases and the boiler to a sufficient extent. Only after this is done, can the engineer without danger to himself and to the boiler, fill the latter up to the normal or mean water level.

Aspiration of the contents of the boiler 10 into the water supply line is prevented by the gap between faucet *h* and funnel *g*. If during the feeding of the boiler the pressure in the water main is reduced for some reason, the only effect will be the aspiration of air 15 through the open faucet *h*. Consequently the contents of the boiler are not affected and burning and deformation of the boiler parts are avoided.

The present invention is adapted for use 20 not only with low pressure boilers but also with high pressure boilers, since the latter may, while cold, be filled thereby up to a certain water level without using a pump. The invention may also be used in connection 25 with reservoirs or tanks where it is of importance to obtain or retain a certain water level.

Feed pipe *e* is not necessarily connected 30 with the condenser line but may be attached to any part of the boiler below the water level. It is understood that the old direct connection between the water main and the boiler must be removed, so that direct feeding of the boiler no longer takes place.

It should be understood that the present 35 embodiment of the invention is merely illustrative of the invention and that various changes in the apparatus could be made without departing from the true spirit of the invention.

Having thus described my invention, I claim:

1. The combination with a steam generating boiler having a water holding chamber 40 and arranged for operation with a predetermined maximum water level in said water holding chamber, of a water supply main, and means for supplying feed water from said main to the lower portion of said water holding chamber comprising a conduit connection extending between said main and said boiler and having a section arranged above and below the maximum water level to be maintained in said water holding chamber, the 45 above mentioned section of said conduit connection having an atmospheric interruption at a level corresponding to the predetermined maximum water level to be maintained in said water holding chamber, a control valve 50 in said conduit connection between said interruption and said main, and a normally closed manually operable valve between said water holding chamber and said interruption, 55 whereby said water holding chamber may not be filled with water above said predetermined maximum water level and whereby water may not be supplied to said water holding chamber from said main while the boiler is under pressure.

mined maximum water level and whereby water may not be supplied from said main to said water holding chamber while the boiler is under pressure.

2. The combination with a steam generating boiler having a water holding chamber and arranged for operation with a predetermined maximum water level in said water holding chamber, of a water supply main, and means for supplying feed water from said main to the lower portion of said water holding chamber comprising a conduit connection extending between said main and said boiler and having a section arranged above and below the maximum water level to be maintained in said water holding chamber, the above mentioned section of said conduit connection having an atmospheric interruption at a level corresponding to the predetermined maximum water level to be maintained in said water holding chamber, the portion of said conduit section immediately below said interruption being formed by a vessel of greater cross-sectional area than the remaining conduit portion between said interruption and said water holding space, a control valve in said conduit connection between said interruption and said main, and a normally closed manually operable valve between said water holding chamber and said interruption, 95 whereby said water holding chamber may not be filled with water above said predetermined maximum water level and whereby water may not be supplied to said water holding chamber from said main while the boiler is under 100 pressure.

In testimony whereof I affix my signature.
LAJOS NEMÉNYI.
